UNITED STATES PATENT OFFICE.

CHARLES B. ISAKSON, OF NEW YORK, N. Y., ASSIGNOR OF ONE-HALF TO
JOHN E. D. ISAKSON, OF BROOKLYN, NEW YORK.

CANDLE-EXTINGUISHER.

SPECIFICATION forming part of Letters Patent No. 767,892, dated August 16, 1904.

Application filed November 13, 1903. Serial No. 181,040. (No model.)

To all whom it may concern:

Be it known that I, CHARLES B. ISAKSON, a citizen of the United States, and a resident of the city of New York, borough of Brooklyn, in 5 the county of Kings and State of New York, have invented a new and Improved Automatic Candle-Extinguisher, of which the following is a full, clear, and exact description.

The object of the invention is to provide a 10 new and improved automatic candle-extinguisher which is simple and durable in construction, cheap to manufacture, easily applied to a candle at any point of its length, and arranged to automatically extinguish the candle 15 after a predetermined length of the candle has been burned.

The invention consists of novel features and parts and combinations of the same, as will be more fully described hereinafter and then 20 pointed out in the claims.

A practical embodiment of the invention is represented in the accompanying drawings, forming a part of this specification, in which similar characters of reference indicate corresponding parts in all the views.

Figure 1 is a perspective view of the improvement as applied. Fig. 2 is a like view of the same, showing the parts in a closed position and the candle-flame extinguished. Fig. 30 3 is an enlarged inverted sectional plan view of the same on the line 3 3 of Fig. 2. Fig. 4 is an enlarged side elevation of the same, and Fig. 5 is a side elevation of the improvement as applied to a candle and arranged as an attachment to a Christmas-tree candle-holder.

The candle-extinguisher is preferably made from a single piece of spring-wire bent to form a clamp having connected clamping members A A' for engaging and clamping the opposite 40 sides of a candle B to support the candle-extinguisher on the candle at any desired point of its length. From the terminals of the clamping members A and A' extend upwardly-converging rods C C', crossing each other and 45 terminating in extinguishing-jaws D D', adapted to engage opposite sides of the candle, as plainly shown in Fig. 1, and to engage and clamp a wick B' when the candle is burned down, so that the liquid fuel to the wick B' is

cut off, and consequently the flame above the 50 clamping-jaws D and D' is extinguished. From the free end of the extinguishing-jaw D' extends downwardly a lug D'', adapted to abut against the extinguishing-jaw D at the time the jaws close to extinguish the flame, as 55 above described, thus limiting the closing movement of the jaws.

In using the device the clamping members A and A' are pressed by the operator in contact with the candle, so as to engage the clamping members with opposite sides of the candle, and at the same time the operator presses the rods C C', so as to move the extinguishing-jaws D and D' apart to engage opposite sides 65 of the candle B a distance above the clamping members A and A'.

The distance from the upper end of the candle to the extinguishing-jaws D and D' regulates the length the candle is to burn, as it is evident that when the candle is consumed down 70 to the jaws D and D' then the resiliency of the spring-wire of which the candle-extinguisher is made causes the jaws to close and move in contact with the opposite sides of the wick B' to squeeze the same sufficiently to prevent 75 liquid fuel from rising in the wick to feed the flame.

The device is very simple and durable in construction and can be readily applied to the candle at any desired point of its length, so as to 80 bring the jaws D and D' nearer to or farther from the top of the candle, according to the length to which the candle is desired to burn.

The candle-extinguisher may form an attachment for the holder F, supporting the candle B, as illustrated in Fig. 5, in which the holder F is in the form of an ordinary Christmas-tree candle-holder having a disk F', retaining-arms F'' for the candle, and an attaching device F''' for fastening the holder to a twig 90 or limb of the Christmas tree. From the free end of the clamping-jaw D extends downwardly a rod E, mounted to turn loosely in the disk F of the candle-holder, so that the candle-extinguisher can be moved up or down on the 95 candle B and still remain connected to the candle-holder. A knob E' on the lower end of the rod E prevents the rod from slipping out of

the disk F'. The use of the candle-extinguisher when forming an attachment of the candle-holder F is the same as above described, and consequently further description of the 5 same is not deemed necessary, it being understood, however, that the rod E is of sufficient length to allow of engaging the candle-extinguisher with the candle at any point of the latter's length, the rod conforming in length 10 to the ordinary candles used on Christmas-tree candle-holders.

Having thus described my invention, I claim as new and desire to secure by Letters Patent—

1. An automatic candle-extinguisher, comprising connected clamping-jaws for clamping the candle, extinguishing-jaws spaced from the clamping-jaws, and connecting-rods connecting the terminals of the clamping-jaws with the said extinguishing-jaws, the said connecting-rods crossing each other, as set forth. 15

2. An automatic candle-extinguisher comprising connected clamping-jaws for clamping the candle, extinguishing-jaws spaced from the clamping-jaws, and connecting-rods connecting the terminals of the clamping-jaws with the said extinguishing-jaws, the said connecting-rods crossing each other, one of the extinguishing-jaws having a stop for engaging the other extinguishing-jaw, to limit the 25 closing movement of the extinguishing-jaws, as set forth.

3. An automatic candle-extinguisher, comprising clamping-jaws, rods extending from the jaws and crossed, and extinguishing-jaws on the ends of the rods, one of the jaws having a downwardly-extending lug at its free end forming a stop for the other jaw, the whole being formed of wire, as set forth. 35

4. An automatic candle-extinguisher formed of a single piece of wire bent to form clamping members for holding the extinguisher on the candle, and having its ends terminating in extinguishing-jaws, as set forth. 40

5. The combination with a candle-holder, of a candle-extinguisher comprising a clamp, 45 self-closing jaws, and a rod secured to one jaw and having a sliding connection with the said candle-holder, as set forth.

6. The combination with a candle-holder having an apertured base, of a candle-extinguisher having clamping members for securing it to a candle and extinguishing-jaws, and a rod secured to one jaw and extending loosely through the apertures of the base of the candle-holder, as set forth. 50

In testimony whereof I have signed my name to this specification in the presence of two subscribing witnesses.

CHARLES B. ISAKSON.
